PRESSURE RESPONSIVE SWITCH

Max Knobel, Boston, Mass., assignor to Pratt & Whitney Company, Inc., West Hartford, Conn., a corporation of Delaware

Application October 15, 1956, Serial No. 615,928

12 Claims. (Cl. 200—83)

This invention relates to a pressure responsive switch, and more specifically to an electrical switch actuated in response to pneumatic signals.

In the art of pneumatic gaging, a frequently encountered problem is that of operating electrical circuits of one kind or another, such as counting and alarm circuits for example, in response to pneumatic signals which are functions of dimensional parameters being measured. It is rather awkward to convert the pneumatic signal into an electrical equivalent before putting the signal to use, and hence, a switch which can be directly operated by extremely small pressure changes is particularly useful.

In addition, it is further required that the switch of the type described, be light in weight, occupy little bulk, and be relatively inexpensive to manufacture.

In preferred form, the switch of this invention comprises a housing having a bore therein and a plunger member arranged to be movable axially within the bore. A flexible impervious diaphragm is placed over one end of the bore, the diaphragm having its intermediate portion doubled upon itself to form concentric cylindrical walls engaging the bore and plunger respectively so as to guide the plunger within the bore during displacement. At least one pair of flexible reeds are secured together at one end by conductive means, the free ends of said reed pair being fastened to said plunger member and to a fixed support respectively. A pair of conductive contact members each in circuit relation with an electrical source are arranged in the housing. The said one end of the reed pair describe an arcuate path upon displacement of the plunger, so that the touching of the said one end of the reed pair, with either one of said contact members, respectively completes an electrical circuit, whereby the magnitude of the displacement of the plunger determines which circuit is completed.

Accordingly, it is an object of this invention to provide an improved switch of the type described which is simple of construction, and easy to manufacture.

Another object is to provide a reliable switch which occupies a relatively small volume.

A further object is to provide an electrical switch of the type described which is adjustably responsive to changes in input pressure signals.

The novel features which are believed to be characteristic of the invention are set forth with particularity in the appended claims. The invention itself, however, both as to its organization and method of operation, together with further objects and advantages thereof, may best be understood by reference to the following description when read in connection with the accompanying drawings in which:

Figure 1 is a front elevation in section of the switch in accordance with one illustrative embodiment of the invention;

Fig. 2 is a top plan view of the switch shown in Fig. 1 with the protective cover removed;

Fig. 3 is a sectional view taken along the line 3—3 in Fig. 1; and

2

Fig. 4 is a side elevation of the switch shown in Fig. 1 with the protective cover removed in the interest of clarity.

Referring now to Fig. 1 of the drawing, spring housing 5 is indicated generally at 10. A plunger guide plate member 12, internally bored at 14, is secured to housing 10 by means of a number of bolts 16, only one of which is shown on the drawing. The plunger, indicated generally at 18, comprises a rod portion 18a, an enlarged diameter portion 18b, and terminates in a plunger head 18c which is arranged to fit in bore 19 of the housing 10 with a clearance. The housing 10 is adapted to receive a plunger spring 20, which bears against the portion 18b of the plunger. As may be seen from a study of Fig. 1, the portion 18b is resiliently urged against a shoulder in the housing. The bore 19 of the housing is sealed by means of a diaphragm or boot 22, which may be of rubber or other impervious flexible material; the boot 22 is held in position by means of an end plate 24, which is secured to the housing by means of four equally spaced bolts identified by the same number 26. The plate member 24 is centrally tapped at 28 so that it will receive a suitable pipe fitting. As may be seen in Fig. 1, the enlarged diameter of bore 14 in plunger guide member 12 is fitted with a sleeve bearing 30 so that the plunger 18 may be easily displaced axially with a minimum of friction.

The diaphragm or boot 22 has its intermediate portion doubled upon itself, as shown, so as to form concentric cylindrical walls engaging the bore 19 and the plunger head 18c. With this arrangement the diaphragm serves to guide the plunger in its movement within the bore. Further, the shape of the diaphragm is such that it offers constant resistance to the fluid forces applied thereto, and hence, the pressure required to deform the diaphragm is constant over the operating range of the switch. This arrangement is such that the switch is responsive to extremely small changes in pressure.

Next, the device is provided with a pair of reed members 32, 34. The reeds are secured at one end by means of a conductive button 36. The reed 32 is secured to the ends of plunger 18 by means of a contact block 38a and a cover member 38b of insulating material; the block 38a is fitted over a reduced diameter portion of the plunger, the reed 32 being secured thereto by means of cover 38b and bolts 40. In like manner the other reed member 34 is also secured to a contact block 42a of insulating material by means of cover member 42b and bolts 44 and 45. As will be seen from a study of Fig. 1, bolt 44 is recessed so that it is electrically isolated from bolt 45. The block 42a is secured to the plunger guide plate 12 by means of screws 46 (Figs. 3 and 4).

The rod portion 18a of the plunger 18 is arranged for axial displacement within the linear anti-friction bearing 20a, which latter bearing is positioned in the plunger guide plate 12 as shown in Fig. 1 of the drawing. The bearing 20a further serves to align the plunger in the direction of said displacement.

The reed members 32, 34 in the illustrated embodiment are of unequal lengths, so that as the plunger 18 is displaced axially, the button 36 describes an arcuate path. As will be appreciated as the description proceeds, the reeds may be chosen in a variety of ways. Member 32, for example, may be of non-conductive material, since member 34 provides the requisite electrical path upon actuation of the switch. The reeds may have different spring constants, and may be of such selected materials as to be deformable in a predetermined non-linear relationship, whereby to insure snap action and prevent an overrun as contact is made or broken.

70 The contact housing 48 will now be described; this unit contains and supports contact members 50 and 52. In this particular embodiment the members 50 and 52 are

contact screws which are secured to the housing by means of screw bushings 56, 58; they may be adjusted in a direction at right angles to plunger travel to thereby vary the magnitude of plunger displacement required for actuation of the associated electrical circuits. As may be observed from a study of the drawing, the axes of members 50, 52 are displaced somewhat; this is necessitated by the fact that the conductive button 36 describes an arcuate and slightly upward path upon vertical movement of the plunger 18. The housing 48 is recessed at 54 to provide space for movement of the reeds; the housing being fastened to the plunger guide member 12 and housing 10 by means of two bolts 60, 62 screwed into tapped holes 61 and 63 respectively. The entire switch may be mounted on a panel 64 in any convenient manner, such as by means of screws 65.

In order to protect the switch from dust and other deleterious influences, a cover 66 is secured to the housing 48 by means of a bolt 68 screwed into tapped hole 69.

Electrical connection to the switch is made as follows: Wires 70 and 72 are secured to bushings 56 and 58 respectively. The housing 48 is recessed at 74 and 76 (Figs. 3, 4) and wires 70, 72 are brought down and electrically secured to screw contacts 78, 80 which are fastened to housing 48 in the usual manner. The desired electrical circuitry may then be connected to the three terminals 78, 45 and 80, terminal 45 being common to the two circuits.

The operation of the circuit is obvious and requires little explanation: In a contemplated application of the switch, the nozzle 28 is connected to a source of pneumatic signals, i. e., the pressure applied at 28 is a function of a dimension being gaged. In one arrangement, the mechanical and electrical parameters were adjusted so that within a predetermined tolerance range, the conductive button 36 was on the midpoint of the arcuate displacement path, and not touching either contact member 50 or 52. When a piece being gaged was undersize, the pressure to the plunger head 18c would fall off, causing the spring 20 to urge the plunger downward, with plunger part 18b being forced against the shoulder in housing 10. Button 36 was then forced into electrical contact with member 52, and the circuit between terminals 78 and 45 was completed so as to cause a red light or other signal to be energized. When the contrary condition developed, and an oversize work piece was being gaged, the pressure would rise, displacing plunger 18 axially upward and forcing button 36 into contact with member 50. The circuit would thus be completed between terminals 80 and 45, to energize a signal such as a green light for example, so as to visually indicate an oversize condition. The operator may thus continuously gage a number of work pieces by pneumatic means, and the color of the signal lamp or the absence of either light being illuminated, gives him the required information concerning the dimensions of the pieces under test.

While specific embodiments have been shown and described, it will, of course, be understood that various other modifications may yet be devised by those skilled in the art which will embody the principles of the invention and found in the true spirit and scope thereof.

I claim:

1. A pressure switch comprising a housing having a bore therein, a plunger movable axially within said bore, a flexible impervious diaphragm closing one end of said bore, said diaphragm having its intermediate portion doubled upon itself to form concentric cylindrical walls engaging said bore and plunger respectively to guide said plunger within the bore during its movement, a pair of flexible metal reeds, one reed having one end attached to said plunger, the second reed being fixed at one end to said housing, the opposite end of said reeds being attached together, an electrical connection to one of said reeds, and electrical contacts

4
mounted adjustably in said housing in positions between which the joined ends of said reeds operate, whereby movement of said plunger will move said joined end of said reeds from one contact to the other.

2. A pressure switch comprising a housing having a bore therein, a plunger movable axially within said bore, a spring surrounding said plunger and forcing said plunger in one direction, a flexible impervious diaphragm closing one end of said bore, means to adjust fluid under pressure to one side of said diaphragm, said diaphragm having its intermediate portion doubled upon itself to form concentric cylindrical walls engaging said bore and plunger respectively to guide said plunger during its movement, a pair of flexible reeds, one reed having one end attached to said plunger, the second reed being fixed at one end to said housing, and the opposite ends of said reeds being attached together, an electrical connection for one of said reeds, and electrical contacts mounted adjustably in said housing, between which the joined ends of said reeds operate, whereby movement of said plunger will move said joined end of said reeds from one contact to the other.

3. A pressure responsive switch of the type described comprising a housing including a longitudinal bore therein, a plunger member displaceable axially within said bore, a diaphragm member sealing said bore in fluid-tight relation at one end thereof, a source of fluid signals applied to the diaphragm member, at least one pair of reeds secured together at one end by conductive means, the free ends of said reed pair being fastened to said plunger member and to a fixed support respectively, a pair of conductive contact members each in circuit relation with an electrical source, the said one end of the reed pair describing an arcuate path upon displacement of the plunger, so that the touching of the said one end of the reed pair with either one of said contact members, respectively completes an electrical circuit, whereby the magnitude of the displacement of the plunger determines which circuit is completed.

4. A pressure switch according to claim 3 in which the diaphragm member comprises deformable material shaped so as to engage the end of the plunger member, the bore side walls and the end face of the housing in contiguous relation.

5. A pressure switch according to claim 3 in which the said source of fluid signals is a pneumatic gaging signal means.

6. A pressure switch according to claim 3 in which the reed connected to the said plunger member is composed of non-conductive material.

7. A pressure switch according to claim 3 in which the reeds have different spring constants.

8. A pressure switch according to claim 3 in which said pair of contact members are adapted for displacement in a direction at right angles to the direction of plunger displacement, whereby the magnitude of incremental pressure change required to complete the electrical circuits may be initially varied.

9. A pressure switch of the type described comprising a housing including a longitudinal bore therein, a diaphragm member pneumatically sealing said bore at one end thereof, a pneumatic signal means applied to said diaphragm member, a plunger member adapted for axial displacement within said bore in response to incremental pressure changes, at least a pair of conductive reeds secured together at one end, the free ends of said reed pair being fastened to said plunger member and to a fixed support respectively, a pair of conductive contact members each in circuit relation with an electrical source, mounted in spaced relation and adjustable in a direction at right angles to the direction of plunger travel, the said one end of the reed pair describing an arcuate path upon movement of the plunger, so that the touching of said one end of the reed pair with either one of said contact members, respectively completes an electrical circuit, whereby

the predetermined magnitudes of the pneumatic pressure signals determine which circuit will be electrically completed.

10. A pressure switch according to claim 3 in which the reed members are of unequal lengths.

11. A pressure switch according to claim 9 in which the reed members are of unequal lengths.

12. A pressure responsive switch of the type described, comprising a plunger member displaceable axially, at least one pair of reeds secured together at one end by conductive means, the free ends of said reed pair being fastened to said plunger member and to a fixed support respectively, a pair of conductive contact members each in circuit relation with an electrical source, the said one end of the reed pair describing an arcuate path upon displacement of the plunger, so that the touching of the said

one end of the reed pair with either one of said contact members, respectively completes an electrical circuit, whereby the magnitude of the displacement of the plunger determines which circuit is completed.
